W. E. NICKERSON.
ANTIRATTLING DEVICE FOR LEAF SPRINGS.
APPLICATION FILED JAN. 16, 1914.

1,163,621.

Patented Dec. 7, 1915.

UNITED STATES PATENT OFFICE.

WILLIAM E. NICKERSON, OF CAMBRIDGE, MASSACHUSETTS, ASSIGNOR TO EVERETT D. CHADWICK, TRUSTEE, OF WINCHESTER, MASSACHUSETTS.

ANTIRATTLING DEVICE FOR LEAF-SPRINGS.

1,163,621.

Specification of Letters Patent.

Patented Dec. 7, 1915.

Application filed January 16, 1914. Serial No. 812,536.

To all whom it may concern:

Be it known that I, WILLIAM E. NICKERSON, a citizen of the United States, residing at Cambridge, in the county of Middlesex and State of Massachusetts, have invented new and useful Improvements in Antirattling Devices for Leaf-Springs, of which the following is a specification.

This invention relates to devices for use in connection with the pivoted yokes commonly employed in leaf springs for preventing excessive separation of the ends of short leaves from the longer leaves on which they rest. A considerable amount of play is necessarily provided for the leaves within these yokes in order that the leaves may have sufficient freedom of motion to accommodate themselves to the changes in shape which the springs undergo when in use, and the result is that the yokes are apt to turn on their pivots from one side to the other and strike against the adjacent parts, thus producing a rattle which is particularly objectionable when such springs are used in automobiles. My invention is intended to overcome this objection, and resides in a device constructed substantially as hereinafter described in connection with the accompanying drawings, in which:

Figure 1 is a side elevation of a portion of an automobile frame and its supporting spring, with the preferred form of my anti-rattling device applied thereto; Fig. 2, which is drawn to a larger scale, is a longitudinal section through a portion of the spring and applied device; Fig. 3 is a transverse section through the parts shown in Fig. 2; Fig. 4 is a top plan view of the anti-rattling device shown in Figs. 2 and 3; Fig. 5 is an edge view of the same; and Figs. 6 and 7 are perspective views illustrating a somewhat modified form of the device.

In Fig. 1 of the drawings, 2 indicates the front end of a side frame such as is commonly employed in automobiles, 3 indicates the front half of a semi-elliptical leaf spring by which the frame 2 is supported, 4 indicates a cross bar to which the middle portion of the spring 3 is clamped in the usual manner, and 5 indicates a common form of yoke, the ends of which are pivotally mounted on a pin 6 passing through the end of one of the shorter leaves of the spring 3, as shown in Figs. 2 and 3, with the body of the yoke extending upward and across the upper face

of the spring at such a distance above the same as to provide for the necessary relative movements of the adjacent spring leaves under the conditions of use.

In order to prevent the yoke 5 from turning on its pivot 6 and striking against the top of the spring, I interpose between the transversely-extending middle portion of the yoke and the underlying leaf of the spring an anti-rattling device which consists in its preferred form of a disk 7 made of spring metal and curved in one direction as shown in Fig. 5, with notches 8 in its edges at opposite ends of the line of curvature. This disk is applied to the yoke 5 by pressing it flat and sliding it under the transverse portion of the yoke until the notches 8 are brought beneath the same, whereupon the side edges of the disk spring upward and receive the yoke within said notches 8, as shown in Figs. 2 and 3, and this relation of the parts is then maintained by the spring action of the disk, which bears centrally on the underlying spring leaf and at its side edges against the under side of the yoke. The yoke is thus prevented from swinging to one side or the other but the freedom of motion of the spring leaves within the yoke is not interfered with, the disk 7 being itself capable of flattening more or less under the varying pressures imposed upon it.

Another form of the device is shown in Figs. 6 and 7, in which 7' is a substantially rectangular strip of metal having marginal portions 9 which are severed from the body 10 of the strip to the extent indicated by the lines 10, leaving said marginal portions integral with the body of the strip about midway of the length of the same. This strip, after having been cut to the form shown in Fig. 6 and given a slight longitudinal curvature, is given a spring temper, and then the temper is drawn from the marginal portions 9 in such manner that the resiliency of the body portion of the strip is not destroyed, whereupon the device may be combined with a leaf spring such as 3 and its yoke 5 by sliding one end of the strip 7' between the transversely-extending portion of the yoke and the underlying spring and then bending upward the free ends of the soft marginal portions 9 on opposite sides of the yoke, as indicated in Fig. 7. So much of the marginal portions 9 as projects above the top of the yoke may then be cut off, leaving the

yoke embraced between the upturned remnants of said marginal portions, and thereupon the device will operate in the same way and with the same results as the disk 7 above described. The curvature of the strip 7' is lengthwise of the spring 3 while that of the disk 7 is transverse to the length of the spring, but this does not affect the operation.

That form of my device which is shown in Fig. 4 is preferred to that shown in Fig. 7 for the reason that it does not require to have the temper device drawn from any part of it and is otherwise less expensive to manufacture, and also because its contour is free from projecting points which might catch on sponges, wash cloths and the like, but both forms of the device have been found to be efficient for their intended purpose.

I claim as my invention:

1. An anti-rattling device adapted to be inserted between the face of an assembled leaf spring and the transversely-extending portion of a yoke embracing said spring, said device being made of thin spring metal and having a slight continuous curvature in one direction, whereby it is provided on

opposite faces with bearing surfaces adapted to press respectively against said spring and yoke; and being also provided at its side edges with recesses facing toward and adapted to receive the under side of said transversely-extending portion of the yoke. 30

2. An anti-rattling device consisting of a disk made of thin spring metal and having a slight continuous curvature in one direction, 35 said disk being provided at the ends of the line of curvature with recesses facing in the opposite direction from the convex side of the disk, whereby the device is adapted to be inserted between the face of an assembled leaf spring and the transversely-extending portion of a yoke embracing said spring, with the under side of said yoke located in said recesses and the convex side of the device bearing against the face of the spring. 40 45

In testimony whereof, I have hereunto subscribed my name this fifteenth day of January, 1914.

WILLIAM E. NICKERSON.
